SWING

Willard M. Bielby, Bay City, Mich.

Application April 7, 1947, Serial No. 739,881

4 Claims. (Cl. 155—63)

1

This invention relates to play and exercising devices for use in the home, parks, play grounds, and other places of amusement for children.

One of the prime objects of the invention is to provide a unique, ornamental swing suspension device designed to accommodate one or two persons and which is so arranged and constructed, that the child or children can use both the feet and hands to start, stop, and control the swinging action of the device.

Another object is to design a suspension swing that is easy to construct, that is fascinating for children to use, and which simulates a gliding action as it swings through the air.

A further object is to provide a device in which the end supporting panels can be shaped to simulate a horse, giraffe, swan, or other animal or bird.

A further object still is to design a swing that is easy to operate and control and provides yieldable bumpers on the ends to eliminate injury to a child walking into the swing's path when the swing is in operation, or when striking a solid object placed in or moved into the path of swing travel.

With the above and other objects in view, the present invention consists in the combination and arrangement of parts, hereinafter more fully described, illustrated in the accompanying drawings, and more particularly pointed out in the appended claims, it being understood that changes may be made in the form, size, proportions, and minor details of construction, without departing from the spirit, or sacrificing any of the advantages of the invention.

In the drawings:

Fig. 1 is a side-elevational view of my swing, the broken lines illustrating the swinging movement thereof.

Fig. 2 is a top plan view.

Fig. 3 is an end-elevational view.

Fig. 4 is an enlarged, fragmentary view showing detachable seats in position for accommodating small children and babies; and,

Fig. 5 is a plan view thereof.

Fig. 6 is an enlarged, fragmentary view of the hand pumping bar showing the connection of the suspension member thereto.

Fig. 7 is an enlarged, part-sectional view showing the manner of connecting the flexible suspension member to the footrest, bumper and cross-bar assembly.

Referring now more particularly to the drawings in which I have shown the preferred embodiment of my invention. The numerals 10 and

11 indicate the spaced-apart end supports, preferably in the form of panels, and in the present instance shaped to simulate a horse and a swan.

A supporting seat bar 12 spans the members 10 and 11, each end being bifurcated as at 14 to accommodate the panels and the swinging movement thereof, and bolts 15 serve to secure the members in assembled relation, and an upright backrest 16 is mounted on the seat bar, and against which the occupant bears when operating the swing.

Transversely disposed, preferably tubular members 17 and 18 are provided in the respective panel members, and footrests 19 and 20 span said tubular members and are secured thereto by means of eyebolts 21. Bumper members 22 and 23 are provided at the opposite ends of the swing, and can be in the form of a hose, the end of which is plugged as at 24, and the eyebolt 21 extends therethrough, the nut 25 serving to secure the members rigidly together.

Transversely disposed pump bars 26 and 27 are provided in the respective panels, and are disposed so that they can be readily grasped by the occupant of the swing, a bent bolt 28 being provided in the end of each bar, the one end 29 projecting beyond the end thereof, and washers 30 serve to confine the chain, and for a purpose to be presently described.

The device is suspended from suitable supports (not shown), a flexible chain F being provided at each corner as shown, the end link being connected to the eyebolt 21; thence leading upwardly so that the end 29 of the bolt 28 projects through one of the chain links, and washers and

35 a nut 31 serve to secure it in position the bolt extending through the link permitting limited movement of the bolt with relation to said link; thence the chain extends upwardly and is anchored to the ceiling or any other support (not shown), and when the occupant puts his or her feet on the foot boards 19 and 20, grasps either of the pumping handles 26 and 27, and begins a pumping action, the structure will sail through

40 the air with a pleasing, gliding action, and the fact that there are vertically spaced connections to the bars 17 and 26, makes it very easy to start and operate. When two persons are using the swing, the pumping is alternated.

45 While in the present instance I have shown chain for suspending the swing, it will be obvious that this can be of cord or any other flexible material.

50 In Figs. 4 and 5 of the drawings, I have shown detachable seats D which are used for children

too small to operate the device, each structure comprising a seat 32 which is secured to the seat bar by means of bolts 33, the side walls 34 simulating horses or other animals, and the back 35 is preferably flat to bear against the backrest 16, a bar 36 connecting the side walls 34 so that it can be grasped by the child. These detachable seats can be easily mounted and/or removed, and are used as above-described.

While in the present instance I have shown two seats mounted on the seat bar, it is understood, of course, that children using such seats are not big enough to operate the swing, this being done by a grown person or attendant. However, when but one of such seats is utilized, a larger child occupies the seat bar and operates the device in the usual manner.

When the swing is suspended so that it operates close to the floor or ground line, the foot rests 19 and 20 can be omitted as the feet normally engage the members 17 or 18 for operation of the swing and the child can readily get on or off the seat bar.

From the foregoing description, it will be clearly obvious that I have prefected a very simple, practical and attractive play swing for children, which is easy to operate and which has a gliding movement when in motion.

What I claim is:

1. In a device of the class described, the combination of spaced-apart, vertically disposed panel members, a horizontally disposed seat member spanning said panel members and pivotally connected thereto at a point intermediate their height, transversely disposed bars in the lower ends of the panels, and longitudinally disposed foot supports spanning said bars on opposite sides of said panels and connected to said bars, yieldable, projecting bumper bars spanning the foot supports on the opposite sides of the device transversely disposed pump bars mounted in the upper end sections of the panels, and flexible members for suspension from a support said flexible members being secured to said foot supports.

2. The combination set forth in claim 1 in which the yieldable bumper bars are hollow and their ends are plugged, and an eyebolt forms a common connection for each end of each bumper bar, foot support, and transversely disposed bar respectively.

3. The combination defined in claim 1 in which a vertically disposed backrest is mounted on the seat bar at a point intermediate its length, and opposed, complete unitary seat structures are detachably secured to said seat member and bear against said backrest.

4. In a swing device, the combination of horizontally spaced-apart panel members, a horizontal seat bar member spanning said panel members and pivotally connected thereto with the ends of the bar slotted to accommodate said panels, a vertically disposed backrest mounted on said seat bar at a point equidistant from the panels; transversely disposed bars mounted in the lower ends of the panels, longitudinally disposed foot supports spanning said bars on opposite sides of the panels and connected to said bars, pump bars mounted in the upper sections of said panels, and flexible suspension members fixedly connected to the end of said foot supports and loosely connected to the ends of the pump bars respectively.

WILLARD M. BIELBY.
